L. A. CHANCE,
COMBINED SLEEVE HOLDER AND CUFF BUTTON DEVICE.
APPLICATION FILED NOV. 17, 1919.

1,334,348.

Patented Mar. 23, 1920.

INVENTOR:
LOUIS A. CHANCE.

ATTORNEYS.

UNITED STATES PATENT OFFICE.

LOUIS A. CHANCE, OF GRAND FORKS, NORTH DAKOTA.

COMBINED SLEEVE-HOLDER AND CUFF-BUTTON DEVICE.

1,334,348.

Specification of Letters Patent. Patented Mar. 23, 1920.

Application filed November 17, 1919. Serial No. 338,428.

To all whom it may concern:

Be it known that I, LOUIS A. CHANCE, a citizen of the United States, residing at Grand Forks, in the county of Grand Forks and State of North Dakota, have invented certain new and useful Improvements in Combined Sleeve-Holder and Cuff-Button Devices, of which the following is a specification.

10 My invention relates to a combined sleeve holder and cuff button device. An object of my invention is to provide a device which will not only serve as a means for carrying the cuff buttons, but will hold the cuffs in proper position around the wrist of the wearer and, when desired, will hold the cuffs up out of the way upon the larger portion of the arm. An object in particular is to provide a device of this character which 15 may be adjusted according to the size of the wrist of the wearer as well as to accommodate the device for cuffs of different size.

20 The full objects and advantages of my invention will appear in connection with the detailed description and the novel features embodied in my inventive idea will be particularly pointed out in the claims.

25 In the accompanying drawings,—

30 Figure 1 is a view in side elevation of one form of my device, showing it positioned to hold the sleeve and attached cuff upwardly on the arm. Fig. 2 is a view of the form of device shown in Fig. 1, this 35 view being mostly in section and showing the clip positioned between the portions of a soft cuff. Fig. 3 is a view partly in section of a modification. Fig. 4 is an elevational view of another modification.

40 Referring to the construction shown in Figs. 1 and 2, the characters 10 and 12 designate complementary members which together constitute a resilient clip having the two free ends juxtaposed, but preferably 45 slightly spaced from each other when in normal position. The clip, when the two members are assembled, is bow-shaped and preferably of oval form. The two members 10 and 12 are adjustably held together 50 by means of rivets 14 secured to one of the members and which extend through a slot 16 in the other member. The rivets have a frictional fit in the slot sufficient to hold the members in desired adjusted position under 55 ordinary conditions, but upon the application of force in the direction of the lengths

of the two members a sliding movement is produced which enlarges or diminishes the bow according to the direction in which the force is applied. Cuff buttons 18 are attached to the free ends of the clip in any suitable manner. A convenient means of attaching these buttons is shown in Fig. 2, in which the main portion of the button is provided with a screw threaded stem 20 which passes through a hole in the end of the clip and screws into a screw threaded hole in the base member 22. Fig. 3 shows a modification in which one clip member is provided with a hollow end or socket portion 26 which is adapted to receive the corresponding, but smaller, end of the complementary clip member 28. The end of the member 28 has a frictional fit in the socket 26 sufficient to retain it in any desired adjusted position. The clip members shown in Figs. 1, 2 and 3 are preferably formed of flat metal pieces which are bent into the proper curved form. Fig. 4 shows another modification in which the two clip members 30 and 32 are formed of wire, the co-operating ends of which are bent into loops 34 and 36 respectively. The loop of each member extends around the other member so that adjustment may be made by a sliding movement of the loops in either direction, as desired.

45 The operation and advantages of my invention will be readily understood from the foregoing description. Fig. 1 shows the operation of the device when it is desired to hold the sleeves and attached cuffs out of the way in upward position upon the arm of the wearer. Since the slit in the cuff is not held firmly together by the cuff buttons, as usual, the cuff will expand together with the clip when the sleeve is pulled upwardly on the arm and the resiliency of the clip will cause it to grip the arm and hold the cuff in any desired position somewhat above the 50 wrist. It is obvious that the clip should have a sufficient curvature so that it will not grip the wrist of the wearer when the cuff is in its normal position. By making the clip adjustable at its middle the necessity of providing different sizes of the clips for different persons is avoided, since by adjusting the two members outwardly the device is expanded and adapted for a larger 55 wrist, and by adjusting the two members inwardly the clip is rendered suitable for smaller wrists. The clip is in this manner

expanded or contracted according to the size of the wrist of the wearer and although this is the most important function of the adjustable construction yet at the same time 5 the clip is adjusted approximately in accordance with the size of the cuffs.

I claim:

1. A combined sleeve holder and cuff button device comprising a resilient clip having free ends which are juxtaposed, cuff buttons attached to said free ends, and means located at substantially the middle of said clip whereby it can be expanded or contracted to vary the width of the clip to accommodate different sized wrists.
2. A combined sleeve holder and cuff button device comprising two complementary members which together constitute a resilient clip having free ends which are juxtaposed, cuff buttons attached to said

free ends, and means for adjustably connecting said members substantially midway between said free ends to vary the width of the clip to accommodate different sized wrists.

3. A combined sleeve holder and cuff button device comprising two complementary members which together constitute a resilient clip having free ends which are juxtaposed, cuff buttons attached to said ends, and means for slidably connecting said members substantially midway between said free ends whereby said clip can be expanded or contracted to vary the width of the clip to accommodate different sized wrists.

In testimony whereof I hereunto affix my signature.

LOUIS A. CHANCE.
